(57) CLAIM

The ornamental design for a suburban mail box with checkered race car flag, as shown and described.

DESCRIPTION

FIG. 1 is a perspective view of a suburban mail box with checkered race car flag showing my new design;

FIG. 2 is a top plan view thereof;

FIG. 3 is a side elevational view thereof with raised checkered race car flag;

FIG. 4 is a front elevational view thereof with raised checkered race car flag;

FIG. 5 is a rear elevational view thereof with raised checkered race car flag;

FIG. 6 is a perspective view thereof with lowered checkered race car flag and stock race car suburban mail box open; and,

FIG. 7 is a perspective view thereof, the race car flag is shown separately for purposes of illustration.

The broken lines in FIGS. 1 through 6 are for illustrative purposes only and form no part of the claimed design.
